[57] CLAIM

The ornamental design for a feline scratch pad, as shown and described.

DESCRIPTION

FIG. 1 is an environmental perspective view of a feline scratch pad showing my new design;

FIG. 2 is a front elevational view thereof;

FIG. 3 is a rear elevational view thereof;

FIG. 4 is a top view thereof;

FIG. 5 is a right side elevational view thereof;

FIG. 6 is a left side elevational view thereof; and,

FIG. 7 is a bottom view thereof.

The broken line showing of the floor line is for illustrative purposes only and forms no part of the claimed design.

FIG. 1

FIG. 3

FIG. 2

FIG. 5

FIG. 6

FIG. 4

FIG. 7
